STOP COUNTER

Elmer W. Larsen, Elmhurst, Ill., assignor to Western Electric Company, Incorporated, New York, N. Y., a corporation of New York

Application October 26, 1937, Serial No. 170,079

10 Claims. (Cl. 235—122)

This invention relates to stop counters, and more particularly to a revolution counter and stop device for coil winding machines.

Objects of the invention are to provide a stop counter which is efficient, compact, durable, readily adjustable, and easily and quickly resettable. In accordance with the above objects, one embodiment of the invention contemplates the provision of a revolution counter and stop device comprising a rotary dial adapted to be driven by either of three concentric driving sleeves. The dial is marked with equidistantly spaced graduations and the driving sleeves are arranged to be driven in the same direction but at different speeds from the rotary shaft or member to be controlled, the relative speeds of the driving sleeves with respect to the member under control and with respect to each other being such that each unit graduation on the dial will correspond to the extent of movement of the dial for either 1, 10 or 100 revolutions of the member under control, according to which one of the three driving sleeves is operatively connected to the dial. Adjustable stop means is provided for varying the initial or starting position of the dial and a stop switch is arranged to be operated under the control of the dial upon the completion of a predetermined number of revolutions of the member under control in accordance with the starting position of the dial as determined by the setting of the stop means.

Other features and advantages of the invention will become apparent from the following detailed description when read in conjunction with the accompanying drawing, in which

Fig. 1 is a front elevational view, partly in section, of a revolution counter and stop device embodying the invention;

Fig. 2 is a vertical sectional view taken on line 4—4 of Fig. 1;

Fig. 3 is a fragmentary sectional view taken on line 3—3 of Fig. 1, and

Fig. 4 is a detail section on line 4—4 of Fig. 1.

Referring first particularly to Fig. 2, it will be seen that the supporting structure of the device comprises a cup-shaped gear housing 10, a second cup-shaped housing 11 superimposed on the gear housing, and a cover or face plate 12. The bottom of housing 11 serves as a cover for the gear housing.

A counter driving shaft 15 is rotatably journaled in the two housings, as shown in Fig. 2, and the outer end of this shaft may be provided with suitable means (not shown) for connection with a winding arbor or other rotary member to be

controlled. A fixed shaft or center post 16 is mounted within the housings in spaced parallel relation with respect to driving shaft 15. Three sleeves 17, 18 and 19 are concentrically mounted on fixed shaft 16 so as to be rotatable with respect to each other. Inner sleeve 17 is rotatable on the fixed shaft, outer sleeve 19 is rotatable within a hub portion 20 of housing 11, and intermediate sleeve 18 is rotatable between the inner and outer sleeves.

A driving pinion 22 is fixed to driving shaft 15 and is in driving engagement with a gear 23 fixed to or integral with inner sleeve 17. A pinion 24 is fixed to or integral with the sleeve and is in driving engagement with a gear 25 mounted for rotation on a hub portion 26 of housing 11. Gear 25 carries a concentric pinion 28 which is in driving engagement with a gear 29 on intermediate sleeve 18. A concentric pinion 30 on gear 29 is in driving engagement with a gear 32 which is rotatable on the housing hub portion 26. Gear 32 carries a concentric pinion 33 which is in driving engagement with a gear 34 on outer sleeve 19.

The gear ratios of the above described gear trains are such that for each revolution of the inner sleeve 17, the intermediate sleeve 18 makes $\frac{1}{10}$ of a revolution and the outer sleeve 19 makes $\frac{1}{100}$ of a revolution.

The face plate 12 is provided with a circular opening 36 for receiving an outer ring 37 which is angularly adjustable and adapted to be clamped to the face plate by a pair of diametrically opposed clamping plates 38, 39 (Figs. 1 and 4). An annular dial 40 is rotatable within outer ring 37 and an inner ring 42 is mounted for rotary movement within inner ring 42. An inwardly flanged center disk 43 is mounted for rotary movement within inner ring 42. The front surfaces of the two rings, the dial and disk 43 are all flush with the front surface of the face plate 12.

Center disk 43 is provided with three eccentric holes 44, 45 and 46 in line with the front end surfaces of sleeves 17, 18 and 19, respectively. A driving pin 48 is adapted to be inserted in either of the holes and each of the sleeves has a notch 49 in its front end surface for receiving the inwardly projecting end of the driving pin, whereby center disk 43 may be selectively connected to either of the sleeves simply by inserting the driving pin in the corresponding hole in the center disk. A readily removable cover plate 50 is provided for retaining the driving pin in position.

A screw clamp 52 having an operating handle 53 serves as a convenient means for clamping inner ring 42 to the driven center disk 43 so that

this ring will rotate with the disk. A fixed stop 54 is attached to housing 11 in position to be engaged by a cooperating stop member 55 attached by two screws 56, 58 to the inner surface of inner ring 42 for limiting rotation of this ring in a clockwise direction (Fig. 1). The stop member 55 also serves as a means for clamping the dial 40 to the inner ring.

The dial 40 has a peripheral notch 57 which controls the operation of a mercury tube type stop switch 58. The stop switch is carried by a pivotal frame 59 pivoted at 60 to housing 11. The frame and switch are arranged to be tilted by an oscillatory arm 62 pivotally suspended from a stud 63 fixed to the housing. A pawl 65 is pivoted at 66 to arm 62 and has a tip portion 67. A spring 68 urges the pawl in a clockwise direction (Fig. 1) about pivot 66 and a stop pin 69 on the pawl engages the arm 62 to limit the clockwise movement of the pawl. The spring also serves to urge the pawl toward the right (Fig. 1) so that upon rotation of the dial to the position in which the peripheral notch 57 registers with the tip portion of the pawl, the tip portion drops into the notch, as shown, under the force of the spring. The resulting movement of the pawl swings arm 62 in a direction to tilt the stop switch to the closed position in which it is shown in the drawing.

When the device is to be employed in conjunction with a coil winding machine for stopping the rotation of the coil winding arbor upon the completion of the winding of a predetermined number of turns, the dial 40 is calibrated on its outer surface in terms of revolutions of the winding arbor and the shaft 15 is connected to the winding arbor through suitable speed reducing gears adapted to rotate the dial at the proper speed. For example, in the device illustrated in the drawings the dial is marked on its outer surface with 300 equidistantly spaced graduations, which are numbered counter-clockwise in "tens" from "0" to "300." In connecting this device to a coil winding machine arbor, the speed reducing gears selected should be of such a ratio that the dial will be rotated to the extent of one unit graduation for each revolution of the winding arbor when the dial is connected to be driven by the inner sleeve 17. Thus, each unit graduation on the dial will correspond to one turn of winding when the dial is driven by the inner sleeve. Since the intermediate sleeve 18 is rotated at $\frac{1}{10}$ the speed of the inner sleeve, it will be obvious that each unit graduation on the dial will correspond to 10 turns of winding when the dial is driven by the intermediate sleeve; and since the outer sleeve 19 is rotated at $\frac{1}{100}$ the speed of the inner sleeve, each unit graduation on the dial will correspond to 100 turns of winding when the dial is driven by the outer sleeve.

When the device is to be employed in conjunction with the winding of single winding coils, the outer ring 37 is angularly adjusted to a position in which a register mark 75 thereon registers with the zero graduation mark on the dial 40 when the dial is in the "stop" position, i. e. when the portion 67 of pawl 65 is engaged in the peripheral notch 57 of the dial, as shown in Fig. 1. The outer ring is then fixed in the adjusted position by clamping it to the stationary face plate 12 by means of the clamps 38. Now assuming, for example, that the coils to be wound require 280 turns of wire, which correspond to 280 revolutions of the winding arbor, the device 75 is adjusted as follows: First, the center disk

driving pin 48 is inserted through the inner hole 44 of the center disk and into the notch 49 of inner sleeve 17, thus establishing a driving connection between the center disk and the inner sleeve. Then the screw clamp 52 is released by turning screw clamp handle 53 and stop and clamp member 55 is released from the dial 40 by loosening the two screws 56. This permits the dial to be rotated around inner ring 42. Then, while the inner ring is held stationary with its stop member 55 engaging fixed stop 54, the dial is manually rotated in a clockwise direction (Fig. 1) to a position in which the "280" graduation mark thereon registers with the register mark 75 on the fixed outer ring. Assuming that the parts are initially positioned as shown in Fig. 1, it will be seen that at the beginning of the above referred to manual rotation of the dial in a clockwise direction, the peripheral notch 57 in the dial will engage and lift the tip portion 67 of pivoted pawl 65 and thereby swing the pawl in a counter-clockwise direction about pivot 66, against the opposing force of spring 68. During this counter-clockwise movement of the pawl, the stop pin 69 will move away from the rear edge of switch carrying arm 62. Then, as soon as the notch 57 in the dial moves past the tip portion of the pawl, the spring 68 will swing the pawl in a clockwise direction until the stop pin 69 again engages the rear edge of switch carrying arm 62. During this clockwise movement of the pawl the peripheral surface of the dial serves as an inclined cam track for the tip portion of the pawl, whereby the pawl is bodily shifted toward the left (Fig. 1), thus swinging arm 62 toward the left sufficiently to cause the tilting of stop switch 58 counter-clockwise from the closed position illustrated to the open position.

The dial having been manually rotated to the position in which the "280" graduation mark thereon registers with the fixed register mark 75, as explained above, it is then clamped to the inner ring by tightening the clamping screws 56 to draw the stop and clamp member 55 into clamping engagement with the dial, whereby the dial is constrained to rotate with the inner ring. Screw clamp handle 53 is then turned to draw the screw clamp 52 on the inner ring into clamping engagement with center disk 43, so that the inner ring together with the dial are now constrained to rotate with the center disk. This completes the setting of the device for 280 turns of winding.

The device having been set, as described above, the winding of the coil is started. As the winding operation proceeds, the dial turns counter-clockwise with inner ring 42 and center disk 43. Meanwhile, stop member 55 on inner ring 42 recedes from fixed stop 54, the "zero" graduation mark on the dial approaches the fixed register mark 75, and the peripheral notch 57 in the dial approaches tip portion 67 of the pivoted pawl. Upon the completion of 280 turns of winding, the "zero" graduation mark reaches the fixed register mark and, at the same time, the peripheral notch 57 in the dial reaches the position in which the tip portion 67 of the pivoted pawl drops into the notch under the force of spring 68. The pawl is thereby bodily shifted toward the right, thus swinging arm 62 toward the right which causes the tilting of the stop switch 58 to the closed position shown in Fig. 1. The stop switch may be connected by conductors 74 to any suitable electro-magnetic means (not 75

shown) for effecting the stopping of the winding operation upon the closing of the switch.

In order to reset the device for winding additional coils having the same number of turns, it is necessary, only, before starting the winding of each coil, to release inner ring 42 from center disk 43 by a slight turn of screw clamp handle 53 and then, by means of the same handle, turn the inner ring together with the dial in a clockwise direction until stop member 55 again engages fixed stop 54. The screw clamp handle is then again turned in the opposite direction to re-clamp the inner ring to the center disk.

In order to set the device for the winding of coils having different numbers of turns, but less than 300 turns, it is necessary in each case to release the dial from the inner ring and then angularly adjust the dial with respect to the inner ring so that when the stop member 55 engages the fixed stop 54, the graduation mark on the dial which corresponds to the number of turns desired registers with the fixed register mark 75, and then re-clamp the dial to the inner ring.

For winding coils having more than 300 and up to 3000 turns, the center disk 43 is operatively connected to the intermediate sleeve 18 by means of the removable pin 48, so that each unit graduation on the dial will now correspond to ten turns, since the intermediate sleeve is rotated at $\frac{1}{10}$ the speed of the inner sleeve. The setting and resetting of the device for the desired number of turns is then accomplished in the same manner as described above with the exception, of course, that the graduation mark now selected for registration with the fixed register mark 75 will be $\frac{1}{10}$ of the number of turns desired. In a similar manner, for winding coils having more than 3000 turns and up to 30,000 turns, the center disk is operatively connected to the outer sleeve 19, so that each unit graduation on the dial will now correspond to one hundred turns, since the outer sleeve is rotated at $\frac{1}{100}$ the speed of the inner sleeve. The setting and resetting of the device is then accomplished as described above except that the graduation mark now selected for registration with the fixed register mark will be $\frac{1}{100}$ of the number of turns desired.

For winding coils having two windings of a different number of turns, an adjustable stop 70 is provided which is pivotally mounted on the outer ring 37 and is provided with a handle 71 for moving it into or out of the path of stop member 55. A spring pressed plunger 73 is mounted in outer ring 37 and is adapted to engage either of two holes 76, 76 in the stop 70 to frictionally hold the stop in either its operative or inoperative position. In Fig. 1, the stop 70 is shown in its inoperative position, wherein it is frictionally held by the engagement of the plunger 73 with the left-hand one of the holes 76. By turning the handle in a counter-clockwise direction (Fig. 1), the stop 70 may be shifted to its operative position, wherein it is adapted to be frictionally retained by the engagement of plunger 73 with the right-hand one of the holes 76. By first releasing the two clamping plates 38, the outer ring may be manually rotated to adjust the position of stop 70 with respect to the dial and stop member 55.

In setting the device for the winding of double winding coils, the dial is angularly adjusted on inner ring 42 and then clamped thereto, as described above, so that if stop member 55 is in

engagement with fixed stop 54 at the beginning of the winding of that winding of the coil which requires the greatest number of turns, then peripheral notch 57 in the dial will effect the closing of stop switch 58 upon the completion of that winding. The stop 70 is then adjusted with respect to the dial and stop member 55 so that if the stop member 55 is in engagement with the stop 70 at the beginning of that winding of the coil which requires the lesser number of turns, then the peripheral notch in the dial will effect the closing of the stop switch upon the completion of that winding.

Assuming, for example, that it is desired to wind a double winding coil having an inner winding of 80 turns and an outer winding of 280 turns, the device is set in the following manner: First, the dial 40 is adjusted, as described above, so that the "280" graduation mark on the dial registers with the register mark 75 when stop member 55 is engaged with fixed stop 54. Then, with the stop 70 in its inoperative position, as shown, the dial and inner ring 42 with stop 55 are manually rotated in a counter-clockwise direction to a position in which the "80" graduation mark on the dial registers with the register mark 75. Then, while the dial is held in this position, the outer ring 37 is manually rotated to a position in which the stop 70, when shifted to its operative position, will be in the path of stop 55 when the latter is moved in a clockwise direction. The stop 70 is then shifted to its operative position and by manually rotating outer ring 37, the stop 70 is engaged with stop 55. With the parts thus adjusted, the outer ring is clamped to fixed plate 12 by means of the clamps 38.

The above adjustments having been made, the operation of the device, when winding double winding coils of the type referred to, is as follows: At the beginning of the first winding of each coil, the dial and inner ring are manually rotated to a position in which the stop 55 engages the stop 70, as explained above, and in this position the dial and inner ring are clamped to driving disk 43 by means of screw clamp 52. Now, during the winding of the first winding of the coil, the dial turns counter-clockwise with inner ring 42 and driving disk 43, the stop 55 recedes from stop 70 and peripheral notch 57 in the dial approaches the portion 61 of pivoted pawl 65. Upon the completion of the 80 turns required for the first winding, the peripheral notch 57 arrives at the position in which it causes the tilting of the stop switch to the closed position, thereby stopping the winding operation. Before starting the winding of the second or outer winding of the coil, stop 70 is shifted to its inoperative position, screw clamp 52 is released and the dial and inner ring are then manually rotated in a clockwise direction about driving disk 43 to a position in which stop 55 engages fixed stop 54. In this position, the dial and inner ring are then clamped to the driving disk, after which the winding of the second winding of the coil may be started. During the winding of this second winding of the coil, the dial turns counter-clockwise, stop 55 recedes from stop 54 and peripheral notch 57 approaches tip portion 61 of the pivoted pawl in the same manner as described above for single winding coils; and upon the completion of the 280 turns required for the second winding, the notch 57 causes the tilting of the stop switch to the closed position, thereby stopping the winding operation.

Now, before starting the first winding of the next coil, stop 70 is shifted to its operative position, screw clamp 52 is released, the inner ring and dial are manually rotated in a clockwise direction to a position in which stop 55 engages stop 70, and in this position the dial and inner ring are clamped to driving disk 43, as explained above.

From the above description, it will be seen that a simple, compact and self-contained revolution counter and stop device is provided which may be readily connected to any rotatable member, such as a winding arbor, to automatically stop the rotation thereof upon the completion 10 of a predetermined number of revolutions or coil winding turns. It will be apparent, also, that the device is readily and quickly adjustable for any desired number of revolutions or turns within a wide range and that substantially the same 20 high degree of accuracy is obtained for any number of revolutions or turns within the wide range. It will be obvious, also, that the device is readily and quickly resettable, since the resetting operation in no case requires more than one revolution 25 of the dial.

It is to be understood that the invention is not limited to the particular construction and embodiment herein illustrated and described, except insofar as is defined by the appended claims.

30 What is claimed is:

1. A counter comprising a rotary dial, a plurality of driving members for said dial, means for driving said members simultaneously at different angular speeds, and means for selectively connecting the dial to any one of said driving members.

2. A counter comprising a rotary dial, a driving element for said dial, a plurality of driving members for said driving element, means for driving said members simultaneously at different angular speeds, means for selectively connecting the dial driving element to any one of said driving members, and means for detachably connecting the dial to said driving element.

45 3. A counter comprising a rotary dial, a plurality of concentric driving members for said dial, means for driving said driving members simultaneously at different angular speeds, and means for selectively connecting the dial to any one of said driving members.

50 4. A counter comprising a rotary dial, a con-

centric driving disk for said dial, a plurality of concentric driving sleeves for said driving disk, means for driving said driving sleeves simultaneously and at different speeds, and means for selectively connecting said driving disk to any one of said driving sleeves.

5 5. A counter comprising a rotary dial, a driving member for said dial, a shaft for driving said member, a second driving member for said dial, means for driving the second member from the first member at one-tenth the speed of the first member, and means for selectively connecting the dial to either of said members.

6. A counter comprising a rotary dial, a plurality of rotary driving members for said rotary dial, means for driving said members simultaneously in the same direction at different angular speeds, and means for selectively connecting the rotary dial to any one of said members.

10 7. A counter comprising a rotary dial, a plurality of rotary driving members for said rotary dial, means for driving one of said members, means interconnecting said members whereby they are driven simultaneously at different angular speeds, and means for selectively connecting the rotary dial to any one of said members.

8. A counter comprising a rotary dial, a plurality of concentric driving member for said rotary dial, means for driving one of said members, means interconnecting said members whereby they are driven simultaneously at different speeds, and means for selectively connecting the rotary dial to any one of said members.

30 9. A counter comprising a rotary dial, a driving member for said dial, means for driving said member, a second driving member for said dial, means for driving the second member from the first member at an angular speed different from that of the first member, and means for selectively connecting the dial to either one of said driving members.

40 10. A counter comprising a rotary dial, a driving member for said dial, means for driving said member, a second driving member for said dial, means for driving the second member at one-tenth the speed of the first member, and means for selectively connecting the dial to either of said members.
